UNITED STATES PATENT OFFICE.

ALFRED L. HARRINGTON, OF ROSSLYN FARMS, PENNSYLVANIA, ASSIGNOR TO
PITTSBURGH PLATE GLASS COMPANY, A CORPORATION OF PENNSYLVANIA.

PLATE-GLASS SURFACING CAR.

Application filed January 22, 1924. Serial No. 687,706.

The invention relates to cars or trucks for carrying plate glass to be ground and polished beneath a series of grinding and polishing machines in the so called straight away operation, the cars being arranged in a continuous line or series with their ends abutting. In such an operation, it is important that the upper surfaces of the tables and of the glass sheets shall be maintained on the same level, so that the runners of the machines shall pass smoothly from one sheet of glass to the next to avoid breakage, and so that the work of surfacing shall be properly distributed over both sheets during the time the abutting ends of two cars are passing beneath the same runner. To secure this result, it is necessary that the track or runway, upon which the cars travel shall be kept perfectly true and level, and that the distance between the rails and the tops of the various cars shall be maintained uniform. The present improvement is designed to provide means whereby the tops of each pair of cars at their abutting ends are positively maintained at the same level and flush with each other throughout the surfacing operation. A further object of the invention is a provision of means of the character specified in which the overlapping plates employed will clean themselves. One embodiment of the invention is illustrated in the accompanying drawings wherein:

Figure 1 is a plan view of the ends of the two cars containing the improvement. Figs. 2, 3 and 4 are vertical longitudinal sections on the lines II—II, III—III and IV—IV respectively of Fig. 1. And Figs. 5 and 6 are detail views of one of the castings employed, Fig. 5 being a plan view and Fig. 6 a side elevation.

Referring to the drawings, 1 and 2 are body portions of a pair of cars embodying the invention, such cars being provided upon their lower sides with the racks 3 and 4 for moving the cars continuously beneath a series of grinding and polishing machines. At each end of each car are a pair of castings 5, 6 and 7, 8, bolted to the body portions of the cars and carrying the axles 9 and 10 upon which are mounted the wheels 11.

In order to releasably lock the cars together, the mechanism shown in Fig. 2 is preferably employed, such mechanism constituting no part of the present invention and being shown and described in detail in

the copending application of John H. Fox, Serial No. 687,705. This locking means includes a hook 12 carried by the car 2 and another hook 13 mounted upon a shaft 14 carried by the car 1. The shaft is provided with a suitable handle for raising the hook 13 to disengage it from the hook 12, and is preferably eccentrically mounted so that the hook 13 is also moved to the left after it reaches the position illustrated in order to hold the two car ends tightly together. A rocking arm 15 is also pivotally mounted upon a shaft 16 carried by the end of the car 2, and this arm is provided with a link 17 adapted to engage a block 18 on the end of the car 1 so that when the handle 19 carried by the shaft 16 is swung to the right, as indicated by the arrow, the car ends are forced apart, provided the hook 13 has previously been raised to disengage the hook 12.

Any other desired means might be employed for releasably securing the two ends of the car in engagement so that a continuous upper surface is provided upon the series of cars.

The castings 5, 6, 7 and 8 are provided with the interlocking means for holding the car ends against relative movement, in which the present invention particularly resides. These interlocking means comprise the projecting plates or members 20, 21, 22 and 23 carried respectively by the castings 6, 8, 5 and 7. Their construction will be readily understood by reference to Figs. 3 to 6 which show the plates or members in section in Figs. 3 and 4, and in plan and side elevation in Figs. 5 and 6. As indicated in figures referred to, the casting 8 is provided with the plate 21 which carries a wear plate 24 preferably secured in place by means of countersunk rivets 25. This wear plate is preferably beveled at its end as indicated at 26 so that it will more readily pass beneath its cooperating surface on the car 1.

As indicated in Fig. 3, such cooperating surface is provided by means of the plate 27 riveted to the lower face of the car body 1 at its end and positioned to engage the upper surface of the plate 24. The wear plate 27 is also beveled at its end to correspond to the bevel 26 on the wear plate 24. When these parts are in interlocking engagement as illustrated in Fig. 3, the end of the car body 2 can not move upwardly with respect to the car body 1. In order to prevent the

- end car body 1 from moving upwardly with respect to the end of the car body 2, the casting 6 (Fig. 1) is provided with a plate or member 20 corresponding to the plate or member 21, the parts being shown in interlocking engagement in Fig. 4 in which 28 is a wear plate secured to the lower side of the car body 2 and cooperating with the wear plate 29 carried by the plate or member 20.
- 10 In this manner the opposing ends of the car bodies at one side are securely locked against upward relative movement, and this same result is secured at the other side of the car by means of the plates 22 and 23 which co-operate in the same manner as heretofore described in connection with the plates 20 and 21.

In order to hold the car ends against any relative lateral or sidewise movement, the 20 sides of the members 20 and 21 and 22 and 23 engage as indicated at 30 and 31, Fig. 1, the opposing surfaces at these points being beveled as indicated. As will be seen by reference to Figs. 3 and 4, a space is provided opposite the ends of the wear plates 27 and 28 as indicated at 32 and 33, so that any dirt which collects on the opposing faces of the wear plates is carried into this recess and does not wedge between the faces of the 25 wear plates as would be the case if no clearance were provided. There is also an open space at the other ends of the wear plates so that any dirt which is scraped off of the wear plates at this end is free to drop out of the way. The opposing surfaces of the 30 wear plates are so positioned with respect to the tops of the car bodies, that when the parts come together, the upper surfaces of the cars are flush as indicated in Figs. 3 and 4, and the interlocking parts securely hold these faces flush even though there are slight 35 inequalities in the track and even though one car body may settle slightly as compared to another due to wear or other causes. The 40 advantage of the construction will be readily apparent to those skilled in the art.

What I claim is:

1. In combination with a pair of abutting cars having means for locking them together, 50 of means for maintaining the top surfaces of the abutting ends flush, which comprises a plate or member on each car on each side thereof projecting forwardly and engaging a downwardly facing surface on the other car.
2. In combination with a pair of abutting cars having means for locking them together, 55 of means for maintaining the top surfaces of the abutting ends flush, which comprises a plate or member on each car on each side

thereof projecting forwardly and engaging a downwardly facing surface on the other car, the said plates or members on one car lying inside the plates on the other car, with their outer side surfaces in engagement 65 with the inner side surfaces of the plates or members on the other car to lock the car ends against relative sidewise movement.

3. In combination with a pair of abutting 70 cars having means for locking them together, of means for maintaining the top surfaces of the abutting ends flush, which comprises a plate or member on each car on each side thereof projecting forwardly and engaging 75 a downwardly facing surface on the other car, the said plates having their upper surfaces beveled at their ends.

4. In combination with a pair of abutting 80 cars having means for locking them together, of means for maintaining the top surfaces of the abutting ends flush, which comprises a plate or member on each car on each side thereof projecting forwardly and engaging 85 a downwardly facing surface on the other car, the said plates having their upper surfaces beveled at their ends, and said downwardly facing surfaces on the cars also being beveled at their ends.

5. In combination with a pair of abutting 90 cars having means for locking them together, of means for maintaining the top surfaces of the abutting ends flush, which comprises a plate or member on each car on each side thereof projecting forwardly and engaging 95 a downwardly facing surface on the other car, the said plates or members on one car lying inside the plates on the other car, with their outer side surfaces in engagement with the inner side surfaces of the plates or members on the other car to lock the car ends against relative sidewise movement, and such side surfaces being tapered.

6. In combination with a pair of abutting 100 cars having means for locking them together, of means for maintaining the top surfaces of the abutting ends flush, which comprises a plate or member on each car on each side thereof projecting forwardly and engaging 105 a downwardly facing surface on the other car, the plates or members and the parts of the car structures receiving them being arranged so that there are open spaces opposite the ends of the plates or members when such plates or members are 110 115 in interlocking position.

In testimony whereof, I have hereunto subscribed my name this 19th day of Jan., 1924.

A. L. HARRINGTON.
